(57) **CLAIM**

The ornamental design for a pair of mount arms for a visor, as shown and described.

DESCRIPTION

FIG. 1 is a front perspective view of a pair of mount arms for a visor in accordance with our new design;

FIG. 2 is a front perspective view of a first enlarged portion of the pair of mount arms for a visor shown in FIG. 1;

FIG. 3 is a front perspective view of a second enlarged portion of the pair of mount arms for a visor shown in FIG. 1;

FIG. 4 is a right-side elevational view of the pair of mount arms for a visor shown in FIG. 1;

FIG. 5 is a right-side elevational view of an enlarged portion of the pair of mount arms for a visor shown in FIG. 4;

FIG. 6 is a left-side elevational view of the pair of mount arms for a visor shown in FIG. 1;

FIG. 7 is a rear elevational view of the pair of mount arms for a visor shown in FIG. 1;

FIG. 8 is a rear elevational view of an enlarged portion of the pair of mount arms for a visor shown in FIG. 7;

FIG. 9 is a front elevation view of the pair of mount arms for a visor shown in FIG. 1;

FIG. 10 is a front elevational view of an enlarged portion of the pair of mount arms for a visor shown in FIG. 9;

FIG. 11 is a top plan view of the pair of mount arms for a visor shown in FIG. 1;

FIG. 12 is a top plan view of an enlarged portion of the pair of mount arms for a visor shown in FIG. 11;

FIG. 13 is a bottom plan view of the pair of mount arms for a visor shown in FIG. 1; and,

FIG. 14 is a bottom plan view of an enlarged portion of the pair of mount arms for a visor shown in FIG. 13.

The broken lines shown in the drawings represent portions of the pair of mount arms for a visor that form no part of the claimed design.
